UNITED STATES PATENT OFFICE.

JAN MORAWSKI, OF BUENOS AIRES, ARGENTINA.

METHOD OF PRESERVATION BY REFRIGERATION.

1,233,387.

Specification of Letters Patent. Patented July 17. 1917.

Application filed May 24, 1916. Serial No. 99,677.

To all whom it may concern:

Be it known that I, JAN MORAWSKI, subject of the German Emperor, residing at No. 343 B. Mitre street, Buenos Aires, Argentina, 5 have invented certain new and useful Improvements in a Method of Preservation by Refrigeration, of which the following is a specification.

In accordance with the known methods of 10 preservation by refrigeration, the air entirely confined within the preserving chamber or cold storage room, is subjected to refrigeration. In this case, it is quite impossible to conveniently control the temperature, 15 so that meat and other eatables, not capable of resisting exceedingly low temperatures, will freeze and in consequence lose part of their value, or else, the preserving air received by the materials, is not sufficiently 20 cold and will cause the same to decompose. The main drawback, however, of this preserving method is that within the refrigerating chamber or cold storage room, the air grows excessively moist and moldy and in 25 consequence promotes the propagation of bacteria and spores. For this reason, another preserving method has been proposed in which the air within the preserving chambers is renewed or replaced by fresh air 30 which has been conveniently treated; notwithstanding, a sufficient regulation of the temperature is not obtained even in this case, while the consumption of refrigerating medium is enormous, as such fresh or new air 35 from outside must always be cooled, and must also be disinfected and freed from moisture each time before use; it must also be considered that the air from outside always carries with it bacteria and spores, 40 which, if not sufficiently destroyed, will render worse the conditions of the preserving chamber.

The present invention proposes a complete 45 change and to this end a process has been devised in which the air, after being confined within the cold storage room or preserving chamber is continually led anew, in forced circulation, through or over devices in which it is cooled, disinfected, deodorized, 50 filtered and freed from moisture. As it is always the same air which is subjected to treatment, its temperature will thus successively be lowered and it will not each time consume again the same amount of refrigerating medium as would be the case if fresh 55

air were introduced each time from outside; besides, by regulating the speed at which the air is made to circulate or by interrupting the circulation of said air at suitable intervals, the temperature may be exactly adjusted and maintained within a predetermined range of degrees. What has been stated with regard to the refrigerating medium, also applies to the medium for drying and disinfecting, the consumption of which 60 will be much less and the use of the latter will cease entirely as soon as the air has become saturated therewith. A feature of particular importance in this case is the simultaneous deodorization, so that the materials 65 which are being preserved may be kept free from odors, notwithstanding the constant use of the same air; this is of much importance when different kinds of eatables are to be preserved in the same room or container, 70 such as cheese and meat, for instance, as one product will not communicate its odor to the other. The supply of oxygen in the closed air circuit may be obtained by the introduction of peroxid of hydrogen or other similar 75 material into the refrigerating apparatus.

The manner of performing the process will be clearly understood from the accompanying drawing, when considered in connection with the following description. 85

In said drawing:

Figure 1 is a longitudinal vertical section of a railway cold storage van or car, constructed in accordance with the invention.

Fig. 2 is a longitudinal view of a disinfecting apparatus based on the same principles.

Fig. 3 is a modification of Fig. 2.

Referring more particularly to Fig. 1, the car therein shown comprises a body part or casing *a*, the double walls of which are suitably and sufficiently insulated against the outer air by means of a layer of cork compound, or of air chambers from which the air has been evacuated, or the like. The car is also provided with a front room or space 100 *b*, designed to receive a dynamo *c* with its accessory fittings, to be driven by a naphtha motor or other engine, or even by the axle of the wheels of the car, as may be desired. The refrigerating chamber proper is filled 105 with ice or other refrigerating material *e* which is introduced thereinto from the roof, through a sort of conical opening adapted to be closed by a cover *d*; salt may eventually be added to the ice or the like, in order to 110

obtain a larger yield of cold, as well as permanganate of potassium or other similar weak medium for destroying germs and odors. Separated from the above by means 5 of a perforated floor or sieve bottom, is arranged a filtering layer of wood charcoal *f* or other porous mass, so that the water produced by the melting ice which at the same time forms a disinfecting and deodorizing 10 solution, will pass through the layer *f* and drip through a sieve bottom into the water collecting tank *g*, whence any excess will pass off by the tubes *g*² to the second water tank or reservoir *g*¹, from which the water may 15 be discharged when necessary by means of a spout or spouts *h*, the tank *g* being similarly provided with a spout or drain, as shown.

When now the fan or exhauster *i* is operated by means of the motor *k* driven by the 20 dynamo, it will suck in the air contained within the preserving room *l* and impel it through the tube *m*, into the water tank *g*¹ whereby the air will be washed and subjected to a preliminary cooling, whereupon 25 it passes by the tubes *g*² to the water tank or reservoir *g* and thence to the porous layer *f*. After being there subjected to a thorough preliminary cooling and purification, the air passes through the numerous interstices 30 formed in the refrigerating material *e* and enters by openings arranged at the top of the partition into the air shaft *n* where part of the moisture is dispersed; thence, the air passes up through another sieve bottom 35 and through the dry layer (*o*), formed of wood charcoal or other porous material where the air will be freed from moisture, even up to 10 per cent., if so required. The air leaves this compartment through openings or outlets formed at the upper part of 40 the next following partition, and then flows either directly into the preserving chamber *l*, as in Fig. 1, or through a second air shaft *p* and then into said preserving chamber, as 45 in Fig. 2. After successively traveling over this circuit, the air will be rendered dry and cold, within a very short time and to the degree desired, and will at the same time be entirely freed from germs and odors.

50 For the purpose of increasing the aforesaid effects, it may in certain cases be convenient to rarefy and even exhaust the inner air of the car or van. On the one hand, such exhaustion allows of obtaining lower temperatures with less consumption of refrigerating material, and on the other, the liability of development of bacteria and spores is more efficiently prevented and finally, the rarefaction of the air facilitates the access 55 to the germs of putrefaction contained within the air bubbles confined, for instance, within the meat, as by rarefying the air in the preserving room, the air contained in the interior of said bubbles is also extracted 60 and subjected to treatment, and after elimi-

nating the vacuum, air duly treated will again penetrate into the interstices formerly occupied by said air bubbles. For this purpose, in the main pressure pipe *m*, a check valve *q* and a discharge valve *r* are arranged. 70 When this latter is opened and the former is closed, the fan forces the inner air outward. An air pump, a water jet pump or similar device may suitably be provided in order to assist the fan in this operation. 75 The pressure of the air in the inner space is indicated by the pressure gage *t* and the inner temperature may be read from the thermometer *s*, shown in Figs. 3 and 2 respectively. This thermometer may be connected by means of suitable leads to the switch of the motor, so that during operation, when the temperature has reached the desired minimum degree, the motor will be cut off and together with it the fan, and 80 when during the following interval of rest the temperature has risen to a predetermined maximum degree, the motor and the fan will be automatically started again. In this way, the refrigerating temperature will always 85 be maintained within the desired range, determined by the kind of goods in cold storage, while at the same time a considerable saving of refrigerating material is realized.

Exactly the same system as above described, may be employed in connection with automobiles, vessels, refrigerating safes, refrigerating cells and the like, for which purpose it will only be necessary to introduce the corresponding changes in the details of 100 construction. Also, a similar kind of apparatus might be constructed, comprising in its interior the above described devices which might then be connected to separate cold storage or refrigerating chambers, in order 105 to exhaust the air therefrom, subject the same to treatment and again discharge it into said chambers. Such apparatus might also be connected to or placed in communication with suitably arranged ventilating or 110 aerating ducts, as well as with existing air heating ducts, for the purpose of effecting ventilation, or during summer, the cooling of rooms. On receptacles, also on glass coffins containing corpses to be preserved, 115 two screw capped openings may for instance be arranged, by which the inner air is submitted to treatment by means of a separate apparatus, in the manner set forth, and thereupon exhausted and burnt, after which 120 the openings on the coffin or other receptacle are tightly closed.

It will be evident, without further explanations, that the novel process as well as the apparatus described, may be used not 125 only for preserving but also for disinfecting purposes. In many cases, disinfection is already carried out in the apparatus as above set forth. In order to enhance the disinfecting effects, in particular cases, more en- 130

ergetic disinfecting means are to be employed.

For disinfecting purposes, in some cases the use of a more simplified method is recommended, according to which the destruction of pertinacious and tough lived bacteria and spores is realized by means of a most intense cold with the aggregate action of a vacuum.

10 For this latter purpose, a refrigerating apparatus as shown by way of example in Fig. 3. is used. A metallic casing *a'* contains four concentric hollow spaces or chambers. The outermost chamber, *c*, forms the insulating space, from which the air may be evacuated when desired, by means of the connecting branch *d'*. The next following hollow space or chamber *e'* with the connecting branch *g'* communicates through openings 15 *e*² with the third hollow space or chamber *f'* and its connecting branch *h'*. When liquefied gaseous fluid is introduced by branch *h'* into the chamber *f'*, the vapors thereof will pass through the chamber *f'* and into chamber *e'* by way of openings *e*² and will escape from the latter chamber by branch *g*³, extracting heat from the storage room around which they flow. If then the air is still further exhausted through the branch *i'* 20 from the inner chamber or space *l*, closed by means of a strong double cover *u* and eventually divided into compartments,—said air having been previously agitated for the purpose of thoroughly cooling and freeing from moisture the goods to be disinfected,—the atmosphere in the storage chamber will be rendered even more intolerable for any living bacteria which might still be contained therein and will destroy the same 25 after a short time. If necessary, the gaseous fluid (air, helium or the like) may be introduced directly under pressure into the storage chamber. By means of this novel system, the materials to be refrigerated or 30 disinfected, according to the case, will be left completely free from bacteria, that is to say, they will be disinfected by cold, extraction of moisture and ulterior extraction of air. The elimination of the use of 35 strong disinfectants, liable to attack and deteriorate the materials to be disinfected according to the known methods, involves a considerable advantage. The short period of time required by the use of this novel

process, should also be taken into account, 55 as compared with the known processes.

I declare that what I claim as new and desire to secure by Letters Patent, is:

1. The herein described process of preserving and disinfecting by refrigeration, which 60 consists substantially in that the air which fills the preserving or disinfecting chamber, as the case may be, passes repeatedly, with a forced circulatory movement, through devices in which it is cooled, disinfected, deodorized, 65 filtered and dried, substantially as described.

2. The herein-described process of preserving and disinfecting by refrigeration which consists substantially in rarefying the atmosphere of the preserving or disinfecting 70 chamber, in repeatedly circulating a current of air under forced draft through said chamber, and in subjecting the said current of air while in circulation to cooling, disinfecting, deodorizing, filtering and drying 75 treatments.

3. The herein-described process of preserving and disinfecting by refrigeration which consists substantially in circulating a current of air under forced draft through 80 the preserving or disinfecting chamber, in subjecting the said current of air while in circulation to cooling, disinfecting, deodorizing, filtering and drying treatments, and in intermittently interrupting the circulation. 85

4. The herein-described apparatus for preserving and disinfecting by refrigeration, comprising, in combination, means for circulating a current of air under forced draft through a refrigerating chamber, and 90 means for automatically maintaining the temperature of said chamber as controlled by such circulation constantly within predetermined maximum and minimum limits.

5. The herein-described apparatus for preserving and disinfecting by refrigeration, comprising, in combination, a device for circulating a current of air under forced draft through a refrigerating chamber, a motor for driving said device provided with a 95 controller, and a regulating device connected to operate said controller so as to maintain the temperature of said chamber as controlled by such circulation constantly within predetermined maximum and minimum limits. 100 105

In testimony whereof I affix my signature.
JAN MORAWSKI.
